SAMUEL W. HUNTINGTON, OF AUGUSTA, MAINE.

Letters Patent No. 67,432, dated August 6, 1867.

INNER SOLES FOR BOOTS AND SHOES.

The Schedule referred to in these Letters Patent and making part of the same.

TO ALL TO WHOM THESE PRESENTS SHALL COME:

Be it known that I, SAMUEL W. HUNTINGTON, of Augusta, in the county of Kennebec, and State of Maine, have invented a new and useful Inner Sole for Boots or Shoes; and do hereby declare the following to be a full, clear, and exact description of the same, reference being had to the accompanying drawings, making part of this specification, and in which—

Figure 1 is a perspective view, and

Figure 2 a section of an inner sole made in accordance with my invention.

The object of this invention is to produce an inner sole for boots and shoes which shall be water-proof, warm, and cheap, the invention consisting in the application to a piece of woollen cloth or carpeting of a thin layer or sheet of lead, in manner and for the purpose as hereinafter described.

In the above-mentioned drawings the sole is shown as composed of a piece of woollen cloth, *a*, having a sheet of lead, *b*, cemented to its under side, and so as to adhere firmly to it, the edges of the two being properly bound.

An inner sole made in this manner possesses the advantages of being water-proof and warm. It will not crumple or crinkle under the foot of the wearer in walking or while putting it into the boot, but, while possessing considerable elasticity, will accommodate itself and yield to the motions of the foot. In practice it has been found to be very durable, and it can be manufactured and sold at small cost.

I claim the improved inner sole for boots and shoes, as composed of the woollen body *a*, in combination with the sheet *b* of lead, in manner and for the purpose as described.

S. W. HUNTINGTON.
